Primary Examiner — Cynthia R Underwood*(74) Attorney, Agent, or Firm* — Charles E. Baxley(57) **CLAIM**

The ornamental design for a cable retainer device, as shown and described.

DESCRIPTION

FIG. 1 is a front and upper perspective view of a cable retainer device showing my new design;
 FIG. 2 is a front elevational view thereof;
 FIG. 3 is a rear elevational view thereof;
 FIG. 4 is a top plan view thereof;
 FIG. 5 is a bottom plan view thereof;
 FIG. 6 is a left side elevational view thereof;
 FIG. 7 is a right side elevational view thereof;
 FIG. 8 is a front and bottom perspective view thereof;
 FIG. 9 is a front and upper perspective view of a second embodiment of the cable retainer device;
 FIG. 10 is a front and bottom perspective view thereof; and,
 FIG. 11 is a bottom plan view thereof.
 The broken lines depict environment and form no part of the claim.
